CLAIM

The ornamental design for component for an electronic device, as shown and described.

DESCRIPTION

FIG. 1 is a bottom front perspective view of a component for an electronic device showing our new design;

FIG. 2 is another bottom front perspective view thereof;

FIG. 3 is a rear view thereof;

FIG. 4 is a front view thereof;

FIG. 5 is a left side view thereof;

FIG. 6 is a right side view thereof;

FIG. 7 is a bottom view thereof; and,

FIG. 8 is a top plan view thereof.

The dot-dash lines in the Figures and the areas within the dot-dash lines show portions of the component for electronic device that form no part of the claimed design.
